Primary Examiner — Terry A Wallace(74) *Attorney, Agent, or Firm* — Banner & Witcoff, Ltd.(57) **CLAIM**

The ornamental design for an insulating device, as shown and described.

DESCRIPTION

FIG. 1 is a top, front, left perspective view of an insulating device showing our new design;

FIG. 2 is a front view thereof;

FIG. 3 is a right side view thereof; and,

FIG. 4 is a left side view thereof.

The uneven-length and even-length broken lines immediately adjacent to the shaded areas represent unclaimed boundaries of the design. The even-length broken lines showing the remainder of the insulating device are for environmental purposes only and form no part of the claimed design. The contrast in shading represents a contrast in appearance only and does not represent any particular color, material, texture or finish.
